(57) CLAIM

The ornamental design for an outdoor cabinet, as shown and described.

DESCRIPTION

FIG. 1 is a top left perspective view of an outdoor cabinet; FIG. 2 is a top right perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken lines shown in the drawings are included for the purpose of unclaimed portions of the outdoor cabinet, and form no part of the claimed design.
